PAPER BAG WITH LOCKING MEANS THROUGH SLITS

George W. Poppe, Stroudsburg, Pa., assignor to Equitable Paper Bag Co. Inc., Long Island City, N. Y., a corporation of New York

Application October 31, 1955, Serial No. 543,839

11 Claims. (Cl. 229—77)

This invention relates to paper bags used for holding merchandise which a customer is going to take from a store, or which is to be delivered to a shipping room. The invention relates more particularly to means for holding the paper bags closed so that merchandise cannot accidentally become displaced from the bag, and so that shop lifters who have made a purchase in a store cannot open the bag and drop other articles into it.

The invention relates more especially to flat paper bags that have front and rear walls or panels and a flap formed by an extension of the rear panel. In such bags, the panel having the longitudinal seam is always considered the rear panel, and the flap folds across the top of the front panel and then downwardly over the front of the bag. Some bags have a flap which comprises not only an extension of the rear panel but also an extension of the front panel above the fold that joins the flap to the bag. Such an extension of the front wall is shorter than the extension of the rear wall so as to leave a lip of the rearwall part of the flap extending beyond the forward part of the flap.

It is an object of this invention to provide an improved bag of the character indicated, with spaced groups of slits through which a locking element is inserted to keep the bag closed.

In every store and mail order house, there are quantities of waste cardboard, and it is another object of this invention to provide a paper bag with a cardboard locking element which can be made from such waste cardboard. The only cost of the locking element, therefore, when using such waste material, is the labor involved in preparing the locking elements from the waste material. This can be done with the aid of a machine, and what little expense is involved is more than offset for the savings effected by this invention.

One of the principal economies resulting from this invention is the use of less expensive bags. The invention makes it practical to use bags which are of lighter paper stock. Where bags are used with a long flap which folds over to close the bag, this invention makes it practical to use bags with much smaller flaps and bottoms and the saving in paper further reduces the cost of the bags.

Other important advantages and economies resulting from the use of this invention are the elimination of losses which result from merchandise accidentally coming out of the containers in which they are enclosed; and reduction in shoplifting losses in stores which display small articles that the shoplifters can drop into bags with previously made purchases.

It is another object of the invention to provide novel shapes of locking elements for insertion into groups of slits through a bag for holding the bag closed more effectively. One feature of the invention relates to constructions by which the locking element can be inserted quickly and conveniently into the slits and by which the edges of the slits pull together throughout a portion of the slit height to prevent removal of the locking element.

2

Other objects, features and advantages of the invention will appear or be pointed out as the description proceeds.

In the drawing, forming a part hereof, in which like reference characters indicate corresponding parts in all the views,

Figure 1 is a view of the front of a bag with a closed flap and with the bag held closed by a closing element made in accordance with this invention;

Figure 2 is a greatly enlarged sectional view taken on the line 2—2 of Figure 1;

Figure 3 is a greatly enlarged sectional view taken on the line 3—3 of Figure 1;

Figure 4 is a sectional view illustrating the manner in which the head of a locking element passes through the slits in the bag;

Figure 5 is a sectional view showing the way in which the upper and lower edge portions of the slits close in behind the shoulders of the locking element to prevent the locking element from being accidentally dislodged;

Figures 6, 7 and 8 are diagrammatic views showing the way in which the locking element is inserted into a group of slits;

Figure 9 is a view showing a modified construction of the front end of one of the locking elements; and

Figure 10 is a fragmentary view, similar to Figure 1, but on a larger scale, showing another modified form of locking element.

Figure 1 shows a small serrated edge lip bag 15 with a small bottom, a narrow center seam and front and rear panels. The bag has a flap 17 which is in the position indicated by dotted lines when the bag 15 is originally supplied to the store. In order to close the bag, the flap is folded along a transverse fold line 19 into the position shown in solid lines in Figure 1.

The flap 17 may be an extension of only the rear panel of the bag 15 and in such case the bag may have a large bottom or the bag may have the front and rear panels both extending above the fold line 19, as shown in Figure 1, and in this latter case the flap 17 consists of extensions of both the panels which fold forwardly and downwardly at the fold line 19.

In the construction shown in elevation in Figure 1 and shown on an enlarged scale in section in Figure 2, the rear panel of the bag is indicated by the reference character 21 and the front panel by the reference character 22. The flap 17 comprises an extension 23 of the front panel 22, and an extension 24 of the rear panel 21.

There are slits 26 in the two walls formed by the extensions 23 and 24 of the flap 17, and there are similar slits through the rear and front panels 21 and 22 of the bag in position to be in substantial register with the slits 26 in the flap 17 when the flap is folded downwardly into position to close the bag. These slits 26, in substantial alignment with one another, form one group of slits which produce an opening through the flap 17 and all the way through the bag 15. There are other slits 27 in the flap 17 in position to substantially register with corresponding slits 27 in the rear and front panels of the bag 15 when the flap 17 is in closed position. These slits 27 form a group providing an opening extending all the way through the flap 17 and the bag 15; and this group of slits 27 is spaced from the group of slits 26, preferably in a direction transverse of the bag 15.

A locking element 30, of substantially greater length than the distance between the groups of slits 26 and 27, is woven through the slits by being inserted through the group of slits 27 in a rearwardly extending direction and then passed across the rear of the bag 15 and inserted through the group of slits 26 in a forwardly ex-

tending direction. The end portions of the locking element 30 extend in opposing directions beyond the group of slits 26 and 27, as shown in Figure 1. This locks the flap in closed position.

The locking element 30 is made with pointed arrow heads 32 on both ends, and with a mid portion or connecting portion 34 extending between the arrow heads 32, and of substantially less height than the shank ends of the arrow heads 32. The connecting portion 34, of the locking element 30, has a height equal to about one half that of the shank ends of the arrow heads 32. This proportion has proven efficient and effective in use because it leaves enough height in the connecting portion to retain the rigidity of the locking element 30 and at the same time provides shoulders of substantial width at the inner or shank ends of the arrow heads 32.

The height of the arrow heads 32, at their inner or shank ends, is substantially equal to the height of the slits 26 and 27, but must not in any event be more than slightly greater than the heights of the slits since this would make it impossible to insert the arrow heads through the slits without tearing the paper of which the bag 15 is made. If only slightly greater than the slit height, the arrow head can be inserted, as will be explained in connection with Figures 6-8.

Figure 4 shows the way in which the confronting faces of the slits are thrust apart by passage of the arrow head 32. As progressively higher sections of the arrow head 32 enter the slits 26, the confronting edges at the upper and lower ends of the slits are caused to diverge from one another, out of the normal plane of the flap 17. The term "slit" is used herein to designate an opening through the paper of the bag made by severing the paper along a line without removing any material from between the confronting faces of the cut. Slits have a number of important advantages over slots from which paper is removed. In the manufacture of the bags, the bag-making machinery can be operated at much higher speed when there is no waste material to be disposed of. Whenever a bag construction calls for the punching of slots with resulting waste punchings, it is necessary to accommodate the speed of the machine to the rate at which the punchings can be disposed of reliably and without danger of occasional accumulations which require shut down of the machine.

A more important advantage of the slit construction of this invention is that the confronting faces of the slits come together at a point at the top of each slit, and also at the bottom. In order to insert a locking element through the slit, the confronting faces must be displaced from one another forward and aft out of the plane of the panels of the bag. This places the confronting edges in angular relation which results from a slight bending of the paper, and the resilience of the paper tends to flatten out the displaced portions as soon as the force causing the displacement is removed.

Thus passage of the arrow head 32 beyond the group of slits 26 permits the confronting edges to move into positions of reduced angular relation to one another so that the edge of the slit beyond the arrow head 32 pulls inwardly across the back of the shoulder formed by the shank end of the arrow head 32, as shown in Figure 5. This prevents the arrow head from moving back again, because the shoulder, indicated by the reference character 36, comes against the edge face of the slit behind it, and there is no component of force for moving the edge of the slit outwardly to let the arrow come back through the slits 26.

All of the thicknesses of paper through which the locking element 30 extends are shown in the drawing, and Figures 3 and 5 show clearly the way in which part of the edge faces of the slits are located behind the shoulder 36.

When the locking element 30 is inserted through the

groups of slits 26 and 27, some additional running clearance is obtained by having the locking element at a slight angle as shown in Figures 6-8. In the ordinary use of the invention, the user will almost always insert the locking elements 30 in a direction which is not quite normal to the direction in which the slits 26 and 27 extend, unless special care is taken to hold the locking element 30 at right angles to the direction of the slits. The advantage of having the locking element at an angle, as it enters the slits 27, is shown clearly by comparing the successive positions of the locking element shown in Figures 6-8.

Figure 6 shows the point of the locking element 30 inserted through the group of slits 27. Figure 7 shows the locking element 30 after it has been pushed further into the groups of slits 27 and this figure illustrates that the bottom or lower end of the shoulder 36 passes the bottoms of the slits 27 before the maximum height of the locking element 30 reaches the slits 27. Thus even though the maximum height of the arrow head 32 is very slightly greater than the height of the slits 27, it can pass through the slits when the locking element is tilted into a position such as shown in Figure 7.

Figure 8 shows the locking element 30 after it has been pushed still further into the group of slits 27. Since the lower shoulder 36 has already passed beyond the group of slits 27, the locking element 30 can move downwardly as necessary in order to permit the upper end of the upper shoulder 36 to pass the upper ends of the slits 27.

The angular position of the locking element 30 is exaggerated in Figures 6-8 to more clearly illustrate the principle whereby the upper and lower shoulders 36 pass the corresponding ends of the slits 27 at different times. In actual practice, the width of the connecting portion 34 of the locking element, and the distance between the groups of slits 26 and 27, usually make it impossible to turn the locking element 30 to an angle as oblique as that illustrated in Figures 6-8 when passing through the second group of slits 26.

When inserting the locking element 30 through the first group of slits, there is no limit on the obliqueness with which it may be presented to the slits, but after it has passed through one group of slits, it can be moved into only a slightly oblique angle to the other group of slits because the upper and lower edges of the connecting portion 34 come into contact with the upper and lower ends of the first group of slits to limit the angular movement of the locking element.

Figure 9 shows a modified construction for the locking element. In this figure a locking element 40 has an arrow head 42 with shoulders 44 at its rearward end; and these shoulders 44 are made with a rake so that they act as barbs for preventing the locking element from being pulled back through a group of slits after the arrow head has once been inserted through the slits.

This construction shown in Figure 9 makes it considerably more difficult to remove the locking element from the slits. A straight shoulder such as shown on the preceding figures is preferred in most instances because the bags must eventually be opened in order to let the customer remove the contents. The locking element 30, shown in Figures 1-8, with the straight shoulders 36, holds the bag closed with an effectiveness which prevents accidental opening of the bag and which prevents a shop-lifter from opening the bag unnoticed preparatory to dropping a stolen article into the bag. However, a customer can manipulate the edges of the slits so as to clear the shoulders 36 of the locking element 30 much more easily than when the arrow has barbed ends such as provided by the shoulders 44 in Figure 9.

The locking elements of this invention are preferably made of cardboard, and the bag can be opened by tearing the arrow head 32 off the connecting portion 34 of

the locking element. The cardboard is heavy enough so that this would not happen accidentally, and it could not be done by a shoplifter without attracting attention. Cardboard having a thickness of from $\frac{1}{64}$ to $\frac{1}{32}$ of an inch has been found sufficiently strong and stiff to make good locking elements for this invention. Such cardboard is commonly used in packaging and shipping merchandise. Somewhat heavier or lighter cardboard can be used, but if the cardboard is too light it is difficult to insert the locking elements through the slits because the cardboard folds instead of pushing through the slits.

In the description thus far the operation of the locking element has been considered for preventing the forward end of the locking element from pulling back after it has passed through a group of slits. It is also necessary to limit the extent to which the locking element can be inserted into the slits since free passage of the entire length of the locking element through the slits would be just as objectionable as reverse movement of the locking element out of the slits.

In the construction shown in Figure 1, both ends of the locking element 30 are provided with arrow heads 32, and the right hand or rearward arrow head 32 has shoulders 36 which contact with the edges of the slits 27 to limit the forward movement of the locking element in the same way that the shoulders of the arrow at the left hand end of the locking element prevent backward movement of the locking element after it has been inserted.

Although not essential, better results are obtained if the difference between the shoulders of the arrow heads 32 is only slightly greater than, or equal to, the spacing of the slits 26 from the slits 27.

With this construction, very little of the connecting portion 34 extends beyond the far sides of the groups of slits 26 and 27, and this makes the shoulders of the arrow heads catch more effectively against the edge faces near the upper and lower ends of the slits.

Figure 10 shows another construction in which a locking element 50 has a tapered shank 52 extending from an arrow head 54. At the rearward end of the arrow head 54, the tapered shank 52 has a height substantially corresponding to that of the connecting portion 34 of the locking element 30 shown in Figure 1; but from this height at the rearward end of the arrow head 54, the height of the shank 52 increases progressively so that its height at the end most remote from the arrow head 54 is substantially greater than the height of the slits 27. The locking element 50, therefore, can only be pushed through the slits 27 until the height of the locking element in the slits becomes as great as the height of the slits 27. Another modification in the construction of the locking element 50 is the off-setting of the shoulders at the shank end of the arrow head 54. The arrow head illustrated is longer at the top than at the bottom and provides an upper shoulder 56 which is further from the point of the arrow than is a lower shoulder 57.

This construction permits the arrow head to go through slits 26 and 27 which are of less height. It is sufficient for the slit height to be equal to the vertical dimension of the arrow head at shoulder 56 or at the shoulder 57, whichever is of the greater height. The locking element 50 is preferably made so that the height at both of these shoulders is substantially equal. The reduced height of the slits in Figure 10, in proportion to the height of the arrow head 54, makes the locking element 50 more difficult to remove than in the locking element 30 of Figure 1.

The locking element 50 is designed so that the tapered edges of its shank portion diverge at a rate to reach the height of the slits 27 just after the last shoulder 56 of the arrow head 54 passes through the slits 26. This locking element 50 cannot possibly be removed toward the left without tearing the paper, or tearing or doubling over the cardboard of the locking element at its right

hand end. At its other end it operates in a manner similar to the locking element 30 of the previous figures, and it can be backed out of the slits by carefully manipulating the edges of the slits so as to let the shoulders of the arrow pass, but the reduced height of the slits in Figure 10 makes removal more difficult as already explained. The locking element 50 has the disadvantage, when the groups of slits are widely spaced and the taper is quite gradual, that a wedge action of the tapered edges of the locking element shank may tear the slits 27 when used with paper bags made of thin stock.

The groups of slits 26 and 27 are spaced from the fold line 19 and are preferably located about mid way between the fold line 19 and the lower edge of the flap 17. In the constructions illustrated, the slits 26 and 27 extend at right angles to the fold line 19. This is the preferred construction but the slits can be at an acute angle to the fold line 19. They are preferably parallel to one another. It is advantageous to have the groups of slits 26 and 27 spaced from one another in directions transverse of the bag because the location of one group of slits at a substantially lower level than the other, in the direction of the length of the bag, requires that the bag and flap be made longer or reduces the capacity of the bag by bringing the locking means to a much lower level on the bag.

It is important that the groups of slits 26 and 27 extend all the way through the flap and bag, that is, through the front panel of the bag as well as through the rear panel. The reason for this is that the locking element is easily inserted through the groups of slits if the group of slits are accessible at both sides to the person inserting the locking element. It is a simple matter to manipulate the groups of slits so as to open them for receiving the locking element, but if the rear panel of the bag were unslotted and the locking element had to be woven through the slits in the flap and front panel without coming through the rear panel, it would be a difficult manipulation to insert the locking element partly because the inner ends of the group of strips would not be accessible to the fingers when the flap was closed and partly because the operator could not clearly see what he was doing when attempting to weave the locking element into the second group of slits.

The preferred construction of the invention has been illustrated and described, and some modifications have been shown, but other modifications and changes can be made and some features can be used in different combinations without departing from the invention as defined in the claims.

What is claimed is:

1. A paper bag for holding merchandise, said bag having a plurality of thicknesses of paper including front and rear panels and a top flap hinged to the upper end of at least the rear panel and adapted to fold over the other panel and down along said other panel to close the bag, at least two groups of slits spaced from one another and extending through both the front and rear panels, the slits in each group forming an opening through the bag, similar slits in the top flap in position adjacent to those in the panels to extend the opening through the flap when the flap is folded down into closed position, the groups of slits being spaced from one another, a locking element made of separate material from the bag and stiffer than the bag and extending through a plurality of the thicknesses of paper at one group of slits and through a plurality of the thicknesses of paper at the other group of slits, the locking element being longer than the spacing of the groups of slits from one another, end portions on the locking element having a height substantially equal to the height of the slits, and slits of each group having confronting edges severed directly from one another without removal of intervening material so that the confronting edges of the slit meet with one another at junction points at the upper and lower ends of each slit, at

least one of the end portions tapering to a reduced width at its front end to facilitate insertion into the slits and having an abrupt change in width providing a shoulder in position to catch on edges of the slits where they converge adjacent to said juncture points to prevent the locking element from being pulled back through the slits.

2. The paper bag described in claim 1 and in which the locking element is made of cardboard, and the locking element has an abrupt increase in width in position to engage edges of the first group of slits to limit the extent to which the locking element can be inserted through the groups of slits in a forward direction.

3. The paper bag described in claim 1 and in which the slits in the panels extend downwardly away from the flap fold and have their upper ends spaced from the fold line, and the groups of slits are spaced from one another in a direction parallel to the fold line along which the flap is connected to the rear panel of the bag.

4. The paper bag described in claim 3 and in which the locking element has a point at its forward end which is inserted through the group of slits, and there is a second abrupt change in the height of the locking element at a position to engage the edges of the first group of slits when the pointed end of the locking element has passed beyond the second group of slits.

5. The paper bag described in claim 3 and in which the locking element has both ends in the shape of arrow heads with the shank ends of the arrow heads of a height substantially equal to the height of the slits, the shank ends of the arrow heads being spaced from one another by a distance substantially equal to the spacing of the groups of slits from one another so that the shoulders at the shank ends of the arrow heads abut against edge faces of the respective groups of slits to prevent movement of the locking element either way in the direction of the length of the locking element after it has been inserted through the groups of slits.

6. The paper bag described in claim 3 and in which the forward end of the locking element is pointed for insertion through the groups of slits, and in which there is an abrupt increase in the height of the locking element to provide shoulders at the top and bottom of the locking element at a location to engage faces of the slits of the first group when the pointed forward end of the locking element has been inserted far enough through the slits of the second group to bring the abrupt change in height of the locking element at the forward end beyond the slits of the first group.

7. A paper bag for merchandise, said bag having front and rear panels, a group of slits in the bag including a slit extending through the front panel and a similar slit extending through the rear panel near the slit in the front panel, another group of slits in the front and rear panel, similar to the slits of the first group and spaced therefrom in a direction transverse of the length of the bag, a locking element separate and independent from the bag and of substantially greater length than the distance between the groups of slits, the locking element being woven through one group of slits in one direction and extending across the other side of the bag and then through the second group of slits in the opposite direction and having end portions beyond both groups of slits of substantially the same height as the slits, and slits of each group having confronting edges severed directly from one another without removal of intervening material so that the confronting edges of the slit meet with one another at juncture points at the upper and lower ends of each slit, and the locking element having an abrupt reduction in height at both the top and the bottom of the end portions and just beyond the groups of slits so that the abrupt changes in height form shoulders on the locking element in position to contact with the edges of the slits where they converge adjacent to said juncture points for preventing movement of the locking element either way in the direction of the length of the locking element.

8. The paper bag described in claim 7 and in which the locking element is made of substantially heavier paper stock than the material of the bag and the locking element is pointed at both ends in a shape of arrow heads, and the rearward end of each arrow head forms the shoulders for preventing the locking element from being displaced in the direction of its length after it has been woven through the slits.

9. The paper bag described in claim 7 and in which the locking element is made of cardboard so that it can be constructed from waste material around a shipping room or store, and the locking element is pointed at its forward end and has the shoulders in position to constitute the pointed end an arrow head, and in which the portion of the locking element beyond the arrow head tapers to a progressively greater height toward its rearward end and has a height substantially equal to the height of the first group of slits at a distance from the arrow head slightly greater than the spacing of the groups of slits from one another.

10. An envelope bag made of paper and having front and rear panels and a top flap hinged to the upper ends of the panels and made up of extensions of both the front and rear panels, slits through the rear panel, the front panel and the flap with said slits in substantial register with one another and forming a group which provides an opening through which a locking member can pass, another group of slits through the panels and flap and similar to the slits of the first group, the slits of each group being spaced from the fold line which joins the flap to the panels of the bag and being spaced from one another in a direction transverse of the top-to-bottom length of the bag, a locking element independent of and unconnected to the bag, said locking element being longer than the space between the groups of slits and woven through one group of slits from front to back and then through the other group of slits from back to front of the bag whereby any pull on the locking element by the top flap is transverse of the locking element, the locking element having end portions of a height substantially equal to the height of the slits, and slits of each group having confronting edges severed directly from one another without removal of intervening material so that the confronting edges of the slit meet with one another at juncture points at the upper and lower ends of each slit, at least the forward end of the locking element tapering to a reduced width at its front end for convenient insertion through the groups of slits, and the locking element having an abrupt change in height at a distance back from the forward end providing shoulders for abutment with the upper and lower portions of an edge of the slits of the second group where they converge adjacent to said juncture points to prevent retrograde movement of the locking element after it has been inserted through the second group far enough to carry the shoulders past said second group of slits.

11. The envelope bag described in claim 10 and in which the slits of both groups extend downwardly away from the flap fold and the slits have their upper ends spaced from the fold line of the flap and the groups of slits are spaced from one another in a direction parallel to the flap fold, the locking element being separate and independent of the material of the bag and made of paper stock substantially heavier than the material of which the bag is made, and the locking element having an increase in height to a value greater than the height of the slits at a location substantially even with the first group of slits when the locking element has been inserted through the second group of slits far enough to carry the shoulders beyond said second group of slits.
